Des. 236,122
Patented July 29, 1975

236,122

AIR FRESHENER

Jody L. Numbers, Scottsdale, Ariz., assignor to
Envair, Inc., San Antonio, Tex.

Filed Nov. 30, 1973, Ser. No. 420,622

Term of patent 14 years

Int. Cl. D23—04

U.S. Cl. D23—150

FIG. 1

FIG. 2

FIG. 3

FIG. 4

FIG. 5

FIG. 6

FIG. 1 is a perspective view of one embodiment of the design with a fabric-type front panel.

FIG. 2 is a front elevational view of the embodiment of FIG. 1.

FIG. 3 is a side elevational view of the embodiment of FIG. 1.

FIG. 4 is a top view of the embodiment of FIG. 1.

FIG. 5 is a bottom view of the embodiment of FIG. 1.

FIG. 6 is a perspective view of another embodiment of the design with a wood-grained front panel, the only difference residing in the appearance of said front panel.

I claim:

The ornamental design for an air freshener, substantially as shown and described.
